DESIGN FOR A MESSAGE SCROLL

William C. Helms, Oakland, Calif.

Application April 9, 1936, Serial No. 62,028

Term of patent 14 years

To all whom it may concern:

Be it known that I, William C. Helms, a citizen of the United States and a resident of Oakland, in the county of Alameda and State of California, have invented a new, original, and ornamental Design for a Message Scroll, of which the following is a specification, reference being had to the accompanying drawing, forming part thereof, wherein

Figure 1 shows a message scroll embodying the

design of my invention, the scroll being in rolled-up condition;

Figure 2 shows the scroll in unrolled condition; the broken lines indicate that the scroll may be of indeterminate length.

I claim:

The ornamental design for a message scroll substantially as shown and described.

WILLIAM C. HELMS.
